INTERNAL COMBUSTION ENGINE

Charles Joseph Teth, Montevideo, Uruguay

Application November 5, 1936, Serial No. 109,384
In Great Britain November 26, 1935

3 Claims. (Cl. 60—15)

This invention relates to two-stroke internal combustion engines, and has for an object to provide an improved compound expansion engine.

In a two-stroke compound internal combustion engine in accordance with the invention, the high pressure cylinder and the low pressure cylinder are arranged with their axes at an acute angle to form a V and the pistons in the two cylinders are connected to a single crank throw. 5
10 The secondary expansion of the working fluid takes place in the lower end of the low pressure cylinder, that is the end nearest the crankshaft, and the primary expansion takes place in the upper end of the high pressure cylinder. The angle between the two cylinders is such, in relation to the other features of the engine, that transfer of the working fluid occurs directly from the lower end of the high pressure cylinder to the lower end of the low pressure cylinder at the 15 correct point in the cycle.

An object of the invention is the elimination, as far as possible, of heat and pressure losses during transfer of the working fluid, and, with this object in view, short transfer channels are 20 used of such dimensions as to eliminate serious throttling effects.

A feature of the invention is the building up in a low pressure cylinder of a cushioning pressure before working fluid is transferred to it from a high pressure cylinder, the arrangement being such that at the time of transfer, the difference between the pressure in the high pressure cylinder and that in the low pressure cylinder is considerably reduced.

35 A further feature of the invention is the use of the actual working pistons for the precompression of air which is used for scavenging and charging air for the cylinders. Thus, the back of a low pressure piston or of a high pressure piston may be used for this purpose.

The engines work on the 2-stroke cycle, the power stroke of a low pressure cylinder occurring at a point about 120° to 180° later in the crankshaft rotation than does that of the corresponding high pressure cylinder.

Various other objects and advantages of the invention will appear from the following description of particular embodiments of the invention, in which reference is made to the accompanying drawing, the novel features being pointed out in the appended claims.

In the drawing, the figure illustrates in cross section one form of engine embodying the present invention.

55 The engine unit illustrated in the drawing con-

sists essentially of two cylinders, the high pressure cylinder A and the low pressure cylinder B, which latter is of considerably larger diameter than is the diameter of the high pressure cylinder.

The high pressure cylinder contains the working piston P which may be of the conventional trunk piston type and it is this piston which controls the opening and closing of the cylinder ports E which serve for the purpose of evacuating the high pressure cylinder of the partially expanded working fluid and to transfer the fluid into the low pressure cylinder, at appropriate times.

In the cover or head of the high pressure cylinder are located the fuel injection valve F and also the corresponding valve means O which latter serve the purpose of admitting precompressed scavenging- and charging-air, at suitable times, into the high pressure cylinder.

It is to be understood that the admission valve means O are not necessarily of the poppet valve type as shown in the illustration, but that they may be of any other usual form of construction, or may be also of the piston- or sleeve-valve types, if desired, without departing from the invention.

The crankshaft of the engine has a single crankthrow M for each group of two working cylinders which form an engine unit and the connecting rod La takes care of the proper connection of the high pressure piston P to the crankthrow M.

The low pressure cylinder B contains the working piston Q which is preferably of the stepped piston type, with a smaller portion S that may carry the corresponding piston pin to which the connecting rod Lb is fastened. This latter is either conveniently pinned to the connecting rod La of the high pressure piston or else the connecting rod Lb may be fastened in any other convenient manner to the same crankthrow M to which the rod La of the high pressure cylinder is connected.

The upper portion of the low pressure cylinder B may be totally or partially closed by a corresponding cover so that a space I is formed wherein, at appropriate times, the low pressure piston Q will produce precompressed air for the purpose of scavenging and charging the working cylinders.

The interiors of the high- and low-pressure cylinders, A and B respectively are in direct communication by the way of the cylinder ports E of the high pressure cylinder and the transfer channel T.

For the purpose of the final evacuation of the completely expanded working fluid from within the low pressure cylinder B, this latter carries the corresponding valve means H which, in this particular case are shown to consist of rotary-type valves, although any other appropriate type of valve means may be employed for this purpose.

The admission of atmospheric air into the pre-compression space I is by the way of the valve means G and the precompressed air from this space passes at appropriate times into the receiver space R by the way of the valve means U, it being understood that, although the valve means G and U are illustrated as being of the poppet- and rotary-valve types respectively, any other system or type of valves may be employed for the purposes of controlling the provision of precompressed scavenging- and charging-air necessary for the proper function of this engine.

20. The axes of the high- and low-pressure cylinders form an angle of approximately 45°, it being understood that to secure the proper function of the engine, it is not required that these two cylinders be set at an angle of exactly 45°, 25 one with respect to the other, but that their relative angular position may be varied between angular positions of from 20° to about 60°, the exact angle being so chosen with relation to other features of the engine that the cycle difference 30 between the high and low pressure pistons is such that transfer from one cylinder to the other occurs at the correct time.

Concerning the operation of the engine illustrated in the drawing, the sequence of functions 35 taking place within the two working cylinders is as follows:

Let us suppose that a charge of air has been compressed within the high pressure cylinder A and, when its piston arrived at or near its upper 40 dead centre position, fuel has been injected by the valve means F and a power stroke initiated, thus the expanding gases will drive the high pressure piston P outward on a working stroke.

At this time the low pressure piston Q is moving 45 inwardly and is driving out the completely expanded gases by way of the corresponding exhaust valve means H and, on the back of said piston Q atmospheric air is being admitted into the precompression space I through the corresponding valve means G.

The exhaust valve means H does not remain open during the entire inward stroke of the low pressure piston Q, so that, during the last portion 55 of its inward stroke, the low pressure piston Q will compress within the cylinder B and transfer channel T a remainder of inert gases, or else an admixture of inert gases and scavenging air, to a pressure that is substantially equivalent to the pressure at which, at suitable times, the partially 60 expanded working fluid will be released from within the high pressure cylinder A.

When the high pressure working piston reaches a position of approximately 60° before its bottom dead centre it will uncover the cylinder port 65 openings E, thus establishing a direct communication between the interiors of the high- and low-pressure cylinders, by way of the transfer channels T.

As soon as the direct communication between 70 the high- and low-pressure cylinders is established, the pressures prevailing at that moment within both cylinders as well as the transfer channels will become gradually equalised, although during a short period of time after the 75 initiation of the opening of the cylinder ports E,

or a period that may correspond to approximately 10° to 30° crankshaft rotation, the low pressure piston Q may still continue its inward motion.

Somewhat later in the cycle, when the low pressure piston P has reached its inner dead centre position and the maximum back pressure within the low pressure cylinder and transfer channel has thus been attained, the pressures within the high- and low-pressure cylinders and the transfer channel will have been completely equalised 10 and, upon the subsequent outward stroke of the low pressure piston Q, the working fluid which continues to pass in a steady flow from within the high- into the low-pressure cylinder renders useful work within this latter, on its second stage 15 expansion and drives the piston Q outward on a working stroke.

During this period of a working stroke within the low pressure cylinder B, the low pressure piston Q will compress on the back thereof, 20 within the space I, atmospheric air to a pressure that, under normal working conditions is equal to the pressure of release of the working fluid from within the high pressure cylinder A and the air thus compressed is transferred, under the 25 control of the valve means U into the receiver space R in order to be used, to scavenge and charge the high pressure cylinder A for which purpose this latter is provided with the corresponding admission valve means O.

As far as the scavenging and charging of the high pressure cylinder A is concerned, the valve means O will be opened and scavenging air admitted from within the receiver space R, shortly 30 after the initiation of the transfer of the working fluid from within the high- into the low-pressure cylinder, or approximately 10° to 30° crankshaft rotation from the instant when the piston P started to uncover the cylinder ports E, the gas pressure within the high pressure cylinder having 35 dropped to approximately the pressure of the pre-compressed scavenging and charging air.

The valve means O remain open at least for the rest of the period during which the cylinder ports E will also be uncovered and may also be 40 kept open during a short period afterwards if a more accentuated charging or supercharging of the high pressure cylinder A with precompressed air is required, as the case may be.

After the closing of the port openings E and 45 the closing at the same time or else cyclically somewhat later in the cycle, the admission valve means O will also have been closed, the inwardly moving high pressure piston P will further compress the intaken charge of air within the high 50 pressure cylinder A and thus prepare within this cylinder the next combustion and first stage expansion.

At the same time, or during the compression 55 period within the high pressure cylinder A, the working fluid transferred into the low pressure cylinder continues therein its second stage expansion, until near the moment when the low pressure piston Q has reached its farthest outward stroke position and when the valve means H which may be of the rotary valve pattern as shown, or else of any other appropriate type, will put the interior of the low pressure cylinder B into communication with the exhaust mains or the atmosphere, thus starting the evacuation of 60 the completely expanded working fluid from within the low pressure cylinder B.

Shortly afterwards, the high pressure piston P will have arrived at its upper dead centre position and, with the subsequent injection of a fuel 65

charge into the high pressure cylinder A the operating sequences will take place again in the manner just described.

I claim:

- 5 1. A two-stroke compound internal combustion engine comprising a high pressure cylinder, a low pressure cylinder with its axis inclined at an acute angle to the axis of the high pressure cylinder, said cylinders enclosing a receiver space in the angle between them, pistons reciprocable in the high pressure and low pressure cylinders, respectively, and connected to the same throw of a crankshaft, an inlet valve through which fluid is admitted for compression in the upper 10 end of the low pressure cylinder, a valve through which the precompressed fluid is passed to a receiver, a valve through which the precompressed fluid is passed from the receiver to the upper end of the high pressure cylinder, means for 15 causing the expansion of the fluid in this end of the high pressure cylinder, a transfer passage controlled by the high pressure piston through which the expanded fluid is transferred to the lower end of the low pressure cylinder for a secondary expansion therein, and a valve controlling the exhaust of the fluid from the lower 20 end of the low pressure cylinder.

- 25 2. A two-stroke compound internal combustion engine comprising a high pressure cylinder, a low pressure cylinder with its axis inclined at an acute angle to the axis of the high pressure cylinder, said cylinders enclosing a receiver space in the angle between them, pistons reciprocable in the high pressure and low pressure cylinders, respectively, and connected to the same throw of a crankshaft, an inlet valve through which air is admitted for compression in the upper end of the low pressure cylinder

by the upper face of the low pressure piston, a valve through which the precompressed air is passed to the receiver, a valve through which the precompressed air is passed from the receiver to the upper end of the high pressure cylinder, an injection valve for injecting fuel into the upper end of the high pressure cylinder for combustion therein, a transfer passage opened by the high pressure piston towards the end of its working stroke and through which the products of combustion are transferred to the low pressure cylinder for a secondary expansion beneath the low pressure piston, and a valve controlling the exhaust of the products of combustion from the lower end of the low pressure 15 cylinder.

3. A two-stroke compound internal combustion engine, comprising a high pressure cylinder, a low pressure cylinder with its axis inclined to the axis of the high pressure cylinder, pistons reciprocable in the high pressure and low pressure cylinders, respectively, and connected to the same throw of a crankshaft, a short transfer passage between the cylinders opening at one end into the expansion space in the high pressure cylinder and at the other end opening into the lower end of the low pressure cylinder on the under side of the low pressure piston, said passage being controlled by the high pressure piston to transfer the working fluid towards the end of the working stroke of the low pressure piston, a receiver utilizing the space in the angle between the high pressure and the low pressure cylinders, means to admit air compressed in the upper end of the low pressure cylinder into the receiver, and means to transfer such air to the high pressure cylinder.
